CLAIM

(51) LOC (7) Cl. **15-09**

The ornamental design of an outer segment of crusher roll, as shown and described.

(52) U.S. Cl. **D15/123**

DESCRIPTION

(58) Field of Search D15/123; 241/275,
241/293, 294, 300, 296, 297

FIG. 1 is a perspective view of an embodiment of an outer segment of crusher roll;

(56) **References Cited**

FIG. 2 is a left end view of the embodiment of FIG. 1;
FIG. 3 is a right end view of the embodiment of FIG. 1;
FIG. 4 is a front view of the embodiment of FIG. 1;
FIG. 5 is a rear view of the embodiment of FIG. 1; and,
FIG. 6 is a top view of the embodiment of FIG. 1.
